[57] **CLAIM**

The ornamental design for a wallpaper hanger, substantially as shown and described.

DESCRIPTION

FIG. 1 is a perspective view taken from the top side and one end of a wallpaper hanger showing my new design; FIG. 2 is a perspective view taken from the bottom and opposite side thereof;

FIG. 3 is a sectional view thereof taken along line 3—3 of FIG. 1 and shown on an enlarged scale with the handle portion omitted for ease of illustration;

FIG. 4 is top plan view thereof;

FIG. 5 is a bottom plan view thereof;

FIG. 6 is an opposite end elevational view thereof shown on a reduced scale.

FIG. 5

FIG. 4
